UNITED STATES PATENT OFFICE.

JAMES C. HOSFORD, OF MALDEN, MASSACHUSETTS, ASSIGNOR TO MAGEE FURNACE COMPANY, OF BOSTON, MASSACHUSETTS, A CORPORATION OF MASSACHUSETTS.

DESIGN FOR A STOVE.

No. 38,841.

Specification for Design.

Patented Sept. 24, 1907.

Application filed July 25, 1907. Serial No. 385,591. Term of patent 14 years.

To all whom it may concern:

Be it known that I, JAMES C. HOSFORD, a citizen of the United States, residing at Malden, in the county of Middlesex and State of Massachusetts, have invented a new, original, and ornamental Design for Stoves, of which the following is a specification, reference being had to the accompanying drawing, forming part thereof.

The figure is a perspective view of a stove, showing my new design.

I claim:

The ornamental design for a stove, as shown.

JAMES C. HOSFORD.
